UNITED STATES PATENT OFFICE

95,290

DESIGN FOR A CONTAINER FOR FRAGILE ARTICLES

Francis H. Sherman, Palmer, Mass.

Application October 2, 1934, Serial No. 53,459

Term of patent 14 years

To all whom it may concern:

Be it known that I, Francis H. Sherman, a citizen of the United States, residing at Palmer, county of Hampden, and State of Massachusetts, have invented a new, original, and ornamental Design for Container for Fragile Articles, of which the following is a specification, reference being had to the accompanying drawing, forming part thereof.

My new design, reference again being had to said drawing, is for a container for fragile articles, comprising opposed top and bottom sections, a prominent feature being the plurality of pyramidal cell-separating formations of the bottom

section. The number of cells may be varied as the bottom section is dimensionally varied. In Fig. 1 of the drawing a container, showing my new design, is illustrated in elevation, as when closed; Fig. 2 shows the same in perspective, the cover portion being raised; and Fig. 3 is a cross-section of the bottom section on the line 3—3 of Fig. 2.

I claim:

The ornamental design for a container for fragile articles substantially as shown and described.

FRANCIS H. SHERMAN.
